METHOD AND MEANS FOR REWORKING
TEXTILE RINGSCharles R. McGhee and Bryant W. Gossett,
Gastonia, N. C.

Application May 13, 1935, Serial No. 21,208

12 Claims. (Cl. 51—103)

This invention relates to a method and means for re-working worn spinning and twisting rings, and more especially to a device in which the spinning or twisting ring is mounted for rotation while a grinding means engages the worn portion of the ring and grinds these portions so as to present an even wearing surface for the traveler.

Heretofore, spinning rings have been used until the inside portion of the flanges thereof have been worn or scarred by the traveler until these flanges were so rough that they could no longer be used in spinning and twisting yarns. It then became necessary to discard this old ring and insert a new ring, thus causing a great expense in the up-keep of the spinning or twisting machinery. Since many of the rings, after having been used, are slightly oval or elliptical it has been impossible for the methods heretofore provided to refinish these rings properly. It is evident that when a ring, which is not absolutely circular, is mounted for rotation and a fixed grinding tool is applied to the portions of this ring, that during the rotation of the ring certain surfaces will be cut deeper than others. If all of the used spinning or twisting rings were absolutely circular, then the refinishing of the worn portions of the flanges would be a very simple matter, since as a true circular ring rotates, every portion of the ring will assume the same position with respect to its axis of rotation.

It is, therefore, an object of this invention to provide a means for mounting a worn spinning or twisting ring which may not be absolutely circular, and rotating the ring so that the point of application of the grinding tool to the ring will remain in exactly the same position with relation to all portions of the periphery of the ring.

It is a further object of this invention to provide a machine in which the worn spinning or twisting ring is mounted and means for grinding the worn flanges thereof uniformly with relation to the periphery of the ring, a second means for roughly finishing both of these flanges simultaneously and uniformly with respect to each other and a third clutch engaging means for quickly engaging the flange of the ring and rotating it in order that a finer abrasive may polish and finish the ring in finished form.

Some of the objects of the invention having been stated, other objects will appear as the description proceeds, when taken in connection with the accompanying drawings, in which:—

Figure 1 is a plan view of an ordinary lathe with the invention applied thereto;

Figure 2 is a transverse sectional view taken along the line 2—2 in Figure 1;

Figure 3 is an elevation looking at the central portion of Figure 1 and showing the means for limiting the longitudinal movement of the grinding means when said means is in an operative position;

Figure 4 is a sectional plan view taken along line 4—4 in Figure 2;

Figure 4A is a sectional view taken along line 4A—4A in Figure 4;

Figure 5 is a view similar to the central portion of Figure 4 but showing the finishing means in operation instead of the grinding means;

Figure 6 is an enlarged elevation showing the finishing and the grinding means;

Figure 7 is a sectional view through a spinning ring with a traveler mounted thereon, said spinning ring being mounted in a conventional spinning frame.

Referring more specifically to the drawings, the numerals 10 and 11 denote the longitudinal trackways for the lathe upon which are slidably mounted base members 12 and 13, respectively. Members 12 and 13 are connected to each other by means of a cross piece 14, and upon this cross piece is slidably mounted a carriage 15 having bearings 16 and 17 mounted thereon which rotatably support a shaft 18. Shaft 18 has a V-shaped pulley 19 fixedly mounted thereon upon which a belt 20 is mounted. This belt 20 is also mounted on a motor pulley 21 mounted on motor shaft 22 of motor 23, said motor 23 being secured to bars 24 and 25 which are mounted on carriage 15.

The carriage 15 has a bolt 30 threadably secured therein which extends forwardly toward the observer in Figure 1, and projects through a suitable hole in projection 14a extending up from cross piece 14. Bolt 30 has suitable nuts 30a on the end thereof which limit the movement of the carriage 15 when it is moved transversely of the lathe by means of the conventional operating crank 31. It is seen that as crank 31 is turned that carriage 15, motor 23 and the shaft 18 are moved backwardly or forwardly transversely of the machine, thereby moving the operating end of shaft 18 to the proper position.

By moving the nuts 30a upwardly on the bolts 30, the movement, away from the observer, of carriage 15 is reduced accordingly. Thereby, by manipulating these nuts 30a, it is evident that the proper location of the grinding tools on the 55

end of shaft 18 may be obtained for any particular job.

The carriage 15 and the base members 12 and 13 are moved longitudinally of the trackways 10 and 11 by the conventional hand wheel 32, and by turning this wheel the shaft 18 and its associated parts will be moved longitudinally of the trackways 10 and 11. The structure thus far is conventional with the exception of members 30 10 and 30a, but it is deemed necessary to show this much of the old structure in order to more clearly disclose our invention.

Shaft 18 has fixedly mounted thereon an abrading or grinding wheel 33 which has inclined 15 surfaces 33a and 33b to conform to the inside portion of the flanges of a spinning ring and which engages these flanges and grinds them down to a smooth uniform surface. Shaft 18 also has a wheel 34 fixedly secured thereon having 20 grooves 35 and 36 thereon which conform to the flanges of the spinning ring and which engages all of the internal surfaces at the same time and finishes the ring off so as to have the surface in position for placing a final polish on it. This 25 wheel is of metal form and charged with diamond dust so that it will be very effective as a grinding and finishing tool. This wheel 34 is brought into action after wheel 33 has ground off the rough surfaces.

30 The shape of wheels 33 and 34 will be designed to conform to the peculiar shape of the ring being finished.

The other end of the lathe has mounted thereon support 37 on which is mounted chuck 38, 35 and secured in the face of chuck 38 is a stud bolt 40 having rotatably mounted thereon a grooved pulley 41 which is integral with a gear 42. Meshing with gear 42 is a worm 43 mounted on the end of shaft 44, said shaft 44 being 40 mounted for rotation in bearing 45 which is secured to the face of chuck 38.

A pulley 46 is also mounted on shaft 44 and has mounted thereon a belt 47 which is also mounted on the motor pulley 48. Pulley 48 is 45 fixedly secured on shaft 49 of electric motor 50.

It is seen that as the motor shaft 49 rotates that motion will likewise be imparted to shaft 44 to cause the pinion 42 and the groove pulley 41 to rotate.

50 Fixedly secured to the chuck 38 is another member 51 which has slidably mounted therein a rod or shaft 52 which has a restricted portion 53 on the left-hand end thereof, (Fig. 2), around which a compression spring 54 is mounted. The 55 left-hand end of member 51 is closed and restricts the movement of the spring 54 in that direction, and the other end of the spring engages the end of rod 52 to normally force it to the right in Figure 2.

60 The left-hand end of restricted portion 53 has a knob or stop 53a thereon to limit the movement of shaft 52 and its associated parts to the right under the force of spring 54. Pivots secured to the ends of shaft 52 by any suitable means such as bolt 57, are plate members 55 and 56. Between members 55 and 56 are two other grooved pulleys 58 and 59, which pulleys are rotatably mounted on bushings 60a which are disposed on bolts 60 and 61 respectively, (Fig. 4A), 65 which penetrate slots 62 and 63 in members 55 and 56. By providing these slots it is evident that relative adjustment of grooved pulleys 58 and 59 with respect to each other, can be made in order to accommodate different sized rings. It will 70 be noted that rollers 58 and 59 are so mounted that 75

axial movement of the same is permitted. This is necessary when abrading a warped annular workpiece. The abrading tool 33 exerts pressure on the workpiece and holds it against the fixed grooved roller and therefore, if the workpiece is 5 warped out of a common plane, the rollers 58 and 59 are allowed to be moved axially on their bushings 60a and thus both flanges of the workpiece are allowed to engage the fixed roller and thereby the workpiece, at the point of abrading, remains 10 in a constant longitudinal plane. Were it not for this feature of end play of the rollers 58 and 59, a warped workpiece would be cut deeper near one edge than at the other.

A worn ring 64 is adapted to be placed between 15 pulleys 41, 58 and 59 in the same manner as shown in Figure 2 and rotated by means of the grooved pulley 41. When it is in this position it is evident that the point where the ring 64 engages the grooved pulley 41, will remain fixed at 20 all times regardless of whether the ring is a circular ring or whether it is elliptical or oval or non-circular.

The pulleys 58 and 59 will be allowed to move back and forth transversely of the machine under 25 the compression of spring 54 if the ring is not absolutely true, therefore, since the point of contact of ring 64 with grooved pulley 41 remains the same at all times during the rotation of the ring, the proper place for grinding the worn surfaces of this ring should be at this point because there would be no variation in the amount of metal ground off of the ring with relation to the periphery thereof.

When the ring 64 is in this position (Fig. 2), the 35 handle or crank 31 is turned so that the members 33 and 34 will pass to the inside of the ring when the wheel 32 is operated to move these members longitudinally of the machine. In this manner the grinding tool 33 is brought to a position as 40 shown in Figure 4, where it will engage the inside flange of the ring 64 and grind it the desired amount.

In order that the amount of grinding will be uniform on both flanges, a stop is provided (Figs. 45 2 and 3) which comprises a block 66 which is secured to trackway 10 by any suitable means such as a stud bolt 67 and clamping member 68 which firmly clamps block 66 to the trackway. Pivots secured on the upper end of block 66 50 as at 69, is a member 70 having projections 70a and 70b projecting from the lower side thereof in which set screws 71 and 72 are threadably mounted. By referring to Figure 3, it is seen how these set screws are positioned in order to limit 55 the longitudinal movement of the carriage 15 and the grinding tool 33 with relation to the inside flanges of the ring 64. When the grinding tool 33 has been moved so that it will be disposed between the two inside flanges of the ring 64 the 60 member 70 is moved from the position shown in Figure 2 to the position shown in Figure 3 so that the set screws 71 and 72 will be disposed on opposed sides of bracket 74 which is secured to base member 12.

65 When this member is disposed in this position it is evident that only a limited movement can take place in either direction and if it is properly adjusted the exact amount will be ground off of each flange of the ring. It should also be 70 noted that the shaft 52 is so mounted that a certain amount of axial movement will be allowed to this shaft should the ring not be absolutely true with respect to its transverse axis, that is, should certain portions of the top and bottom 75

surfaces of the ring be slightly warped. This affords means for firmly engaging the ring at three points at all times regardless of whether it is true with respect to its longitudinal or its 5 transverse axis.

While grinding a ring it is necessary that a suitable cooling solution be applied thereto in order to prevent the ring from becoming heated and losing its temper. Therefore, a suitable 10 reservoir 75 is provided between the trackways 10 and 11 having a cooling solution 76 which is drawn through pipe 77 into pump 78 and from pump 78 through pipe 79, valve 80 and another pipe 81 which is so disposed that the fluid will 15 be conducted to the ring 64 in order to cool the same while it is being ground.

Pump 78 is driven by a suitable pulley 82 which is secured on the end of the pump shaft and has mounted thereon a belt 83 which belt is also 20 mounted on a second pulley 84 on shaft 44. As the motor turns to impart the power to the grooved pulley 41 and its associated parts, it likewise imparts power to the pump 78 to supply the cooling fluid 76 to the ring as it is being 25 ground.

Figure 7 shows a sectional view through a portion of spinning frame 86 which has a ring holder 87 mounted therein. In the upper end of the ring holder is mounted the spinning ring 30 64 which has a traveler 64b mounted thereon which is adapted to travel around the ring as the yarn is being twisted. As this traveler is turning around at a very high speed, the interior portion 64c will become worn, and after the wear 35 has become excessive, it is necessary to turn the ring over and place the traveler on the other flange. It is then used in this manner until the flange 64d becomes worn. At this time the ring is placed in the apparatus just described, and re- 40 ground to form a finished appearance on the inside surfaces 64c and 64d.

In the drawings and specification there has been set forth a preferred embodiment of the invention, and although specific terms are employed, they are used in a generic and descriptive sense only, and not for purposes of limitation, the scope of the invention being set forth in the appended claims.

We claim:

1. Means for performing an abrading operation on the interior surface of an annular member comprising a roller having a V-shaped groove in its periphery and mounted for rotation at a fixed point, a member slidably mounted with relation to the roller, a pair of other rollers pivotally mounted on said slidably mounted member and each having a V-shaped groove in its periphery, resilient means normally pressing said pair of rollers towards the first roller to hold the annular work 50 piece in position between said three rollers, means for imparting rotation to one of the rollers to impart rotation to the annular work piece, a rotary abrading tool movable into said annular work piece, and means for moving said tool against the interior surface of said annular member while the same is rotating.

2. Means for performing an abrading operation on an annular work piece comprising three rollers having V-shaped grooves in their peripheries, 55 means for driving one of the rollers, means for pivotally and resiliently mounting the other two rollers for rotation, means for pressing said pivotally mounted rollers towards the other roller to hold the work piece between the rollers, a rotary 60 abrading tool insertable into said work piece and

means for moving the tool laterally against the interior surface of the work piece.

3. Means for performing an abrading operation on the interior surface of an annular work piece comprising three V-rollers mounted for 5 rotation in the same plane and being spaced from each other, means for mounting one of the rollers for rotation at a fixed point, a pivoted member for supporting the other two rollers, means normally pressing the pivoted member and its rollers towards the first named roller to hold the work piece between the rollers, means for driving one of the rollers, a rotary abrading tool insertable within the work piece, and means for moving the tool laterally against the interior of 15 the work piece.

4. Means for performing an abrading operation on the interior surface of an annular work piece comprising three rollers mounted for rotation in substantially the same plane and being 20 spaced from each other, a pivoted member for supporting two of the rollers in spaced relation to the third roller, means normally pressing the pivoted member and its rollers towards the third roller to hold the work piece between the three 25 rollers, means for driving one of the rollers, a rotary abrading tool, a movable mounting for the abrading tool, and means for moving the tool laterally against the interior surface of the work piece and towards the third roller. 30

5. Means for performing an abrading operation on the interior surface of a non-circular annular member to cut the member to a uniform thickness at all points, comprising means for holding the member and rotating the same including a roller 35 having a V-shaped groove in its periphery, a member movably mounted with relation to the roller, a pair of rollers mounted in said member and each having a V-shaped groove in its periphery, resilient means normally pressing said 40 pair of rollers towards the first roller to hold the annular work piece in position between said three rollers, means for imparting rotation to one of the rollers to impart rotation to the annular work piece, a rotary abrading tool, a movable mounting 45 for said tool, means for moving said mounting to place the tool into said annular work piece, and means for moving said tool against the interior surface of said annular member while the same is rotating. 50

6. Means for performing an abrading operation on the interior surface of a non-circular annular member to cut the member to a uniform thickness at all points, comprising means for holding the member and rotating the same, including a roller having a V-shaped groove in its periphery, a member movably mounted with relation to the roller, a pair of other rollers mounted in said member and each having a V-shaped groove in its periphery, resilient means normally 55 pressing said pair of rollers towards the first roller to hold the annular work piece in position between said three rollers, means allowing individual axial movement in each of the pair of rollers along the longitudinal axis of the annular 60 member, means for imparting rotation to one of the rollers to impart rotation to the annular work piece, a rotary abrading tool, and means for moving said tool against the interior surface of said 65 annular member while the same is rotating. 70

7. Means for performing an abrading operation on an annular work piece comprising three rollers having V-shaped grooves in their peripheries, means for driving one of the rollers, means for resiliently mounting the other two rollers for ro- 75

tation to press them into engagement with the exterior of the work piece at all times, a rotary abrading tool and means for moving the tool laterally against the interior surface of the work piece.

5. 8. In apparatus for internally grinding a non-circular annular work piece, means for holding the work piece comprising a V-roller mounted for rotation at a fixed point, a pair of other V-rollers 10 mounted for movement towards and away from the first roller, means normally urging each of the pair of rollers into engagement with the exterior of the work piece, means for driving one of the rollers, the pair of rollers being movable towards and away from the first roller by the variations 15 from a true circle in the outer surface of the work piece, and the pair of rollers being movable longitudinally of the axis of the work piece by the variations from a common plane of portions of the work piece.

9. Means for performing an abrading operation on the interior surface of an annular work piece comprising three grooved rollers whose peripheral grooves have diverging side walls and 25 being mounted for rotation in the same plane and being spaced from each other, a movable member for supporting two of the rollers, means allowing individual axial movement of each of said two rollers, means normally pressing the 30 movable member and its rollers towards the work piece to hold the work piece between the rollers, means for driving one of the rollers, a rotary abrading tool insertable within the work piece, and means for moving the tool laterally against 35 the interior of the work piece.

10. Means for performing an abrading operation on the interior of an oval shaped work piece which comprises three rollers spaced from each other and engaging the work piece at three

points, one of the rollers being mounted for rotation at a fixed point and the other two rollers being mounted for rotation on a movable support, means for driving one of the rollers to impart rotation to the work piece, a rotary cutting 5 tool, means for moving the tool laterally to engage the interior surface of the work piece at its point of tangency with said fixed roller, a laterally movable means, said movable support being pivoted at a point equidistant from the rollers to 10 said laterally movable means to cause the radius of the work piece to remain substantially in alignment with the radius of the rotary tool at its point of engagement with the work piece.

11. That method of reworking oval-shaped 15 textile rings which comprises moving by contact all points on the periphery of the ring through a fixed point and maintaining the radius through each point on the periphery of the ring in substantially the same position as each point on the 20 periphery of the ring passes through said fixed point and performing an abrading operation on the interior surface of the ring at a point disposed on the radius through each point on the periphery of said ring as each point on the 25 periphery of the ring passes through said fixed point.

12. That method of reworking oval-shaped 30 textile rings which comprises moving by contact, all points on the periphery of the ring through a fixed point and causing the tangent to each point on the periphery of said ring to occupy substantially the same position as the point on the ring passes through said fixed point, and performing 35 an abrading operation on the interior surface of said ring at a point disposed on the normal to the tangent at said fixed point.

CHARLES R. McGHEE.
BRYANT W. GOSSETT.
